UNITED STATES PATENT OFFICE.

NICOLAS RÉTHORÉ, OF NEUILLY-SUR-SEINE, FRANCE.

TOY TOBOGGAN RAILWAY.

Application filed September 5, 1919. Serial No. 321,978.

To all whom it may concern:

Be it known that I, NICOLAS RÉTHORÉ, of 54 Avenue du Roule, Neuilly-sur-Seine, France, a citizen of the French Republic, 5 have invented certain new and useful Improvements in Toy Toboggan Railways, of which the following is a specification.

This invention relates to a toy which takes the form of a toboggan railway the track of 10 which can be formed of elements put together in a rigid manner or of elements constituted by two flexible and elastic rails in which a limited number of holes is drilled, but allowing of one or the other of the following combinations to be obtained as desired:

A track in the form of a semi-circle.

A bent track.

A partly curved and partly straight track.

20 A track in a straight line.

Or, if preferred, a symmetrical arrangement of these.

This track consisting of rigid or of flexible 25 elements is supported by upright bearers of different heights furnished with cross stays for joining and sustaining them.

Two inclined planes may also be combined on each of which is a car the two cars being united by means of a rope so that one of 30 them on which an extra load is placed, runs down on the track causing the other to run up.

In place of cars, balls or other devices that turn over and over may also be employed.

The annexed drawing given by way of example shows one of the methods of carrying out this invention.

Fig. 1 illustrates the method of putting 40 the rails together for the purpose of constructing a selected track.

Fig. 2 shows a cross-stay ready for receiving the track.

Figs. 3 to 19 illustrate a certain number 45 of forms of the track set up in toboggan style.

Fig. 20 is an elevation of a straight line track.

Fig. 21 is the plan thereof.

50 Fig. 22 illustrates two tracks inclined in opposite directions, forming a funicular railway.

Fig. 23 is the plan on a larger scale of one of the funicular railway cars with the 55 return pulley attached to the rope.

Fig. 24 is the section of a track cross stay.

Fig. 25 is the plan thereof.

Fig. 26 is the transverse section of a car.

Fig. 27 is a half view in elevation and a longitudinal half section.

60

Fig. 28 is a horizontal section thereof.

Fig. 29 illustrates the box in which the various parts of the toy are arranged.

Figs. 30 and 31 represent a short and a long piece of thin metal for the formation 65 of the track composed of flexible and elastic rails.

Fig. 32 is a half section and a half elevation of what is assembled on the cross-stay.

Fig. 33 are respectively horizontal sec- 70 tions and a plan thereof.

Fig. 34 illustrates various cross-stays of different heights.

This invention consists in the creation of a toboggan railway which can be taken to 75 pieces and be set up in different forms with track composed of rigid or of flexible rails, supported by removable cross-stays.

Preferably flexible spring pieces of thin 80 metal are used as rails enabling various forms of track to be constructed. With this idea a certain number of short spring rails (Fig. 30) have been provided for and an equal number of long spring rails (Fig. 31).

The short spring rails are drilled at *a*, *b*, *c*, *d*, *e*, *f*, *g*, *h*, *i*, *j*, and the long spring at *A*, *B*, *C*, *D*, *E*, *F*, *G*, *H*, *I*, *J*, in the manner indicated in Figs. 30 and 31.

These rails are fixed on cross stays 85 (Figs. 24 and 25) by means of pins 21 one of the ends of which terminates in a head and the other in a point on which a piece 22 can be placed which is made of india rubber for example and serves at the same time as 90 a point protector and as a retention device.

For the purpose of setting up a selected track the spring rails are assembled by means of their cross stays preferably flat-wise on a table the indications given in 100 Fig. 1 being followed.

With this object "forms" furnished with grooves in the places corresponding to the pins may be used so as to get rid of any trouble concerning the holes to be connected.

105

In order to form the toboggan in a curved form or in a straight line the track is placed on upright supports (Fig. 34) of different heights provided with cross-stays arranged at various heights. These upright supports 110 have pivoted feet which come cross-wise so as to increase the stability.

One and the same upright support may support the track at different heights. In order to fix the track placed on the cross stays for the upright supports large pins are employed (Figs. 2 and 32) which are inserted in T eyelets in the upright supports. The heads of the pins are then pushed against the eyelets in the uprights, their other extremity entering the opposite eyelets S.

The joints P, Q, show that the upper rails come in the interior of the track the lower rails outside, the former being always assembled by means of their extreme holes whilst the latter can also be assembled by means of a last but one hole *i* or I.

Numerous variations in the configuration and the arrangement of the track can also be effected: superposed crowns spirally arranged (Fig. 3) crown and straight line (Fig. 4) a figure 8 (Fig. 5), etc., (Figs. 6 to 21). By joining two upright supports a shoot can be formed on the track (Figs. 6 and 9).

Figs. 6 and 7 show that the track can also be placed partly on upright supports and partly flatwise on a table for example. It could even be placed entirely flat-wise.

It is also possible to create a sort of funicular railway (Fig. 22) by combining two differently sloping tracks and causing two cars to run thereon which are joined together by a rope R R' that runs over a pulley X (Fig. 23) supported by two cross-stays V made of metal tubing for example.

Cars preferably of the kind shown in Figs. 26 to 28 may be employed. In these cars the mounted axles are removable and can be moved in the oblong holes 25^a so facilitating movement in curves.

These axles are supported by thin cut out pieces of metal 25 which are fixed by means of eyelets on the sides of the cars. The elasticity of these thin metal pieces enables them to be put apart at their lower end for

the purpose of withdrawing the mounted axles.

In place of cars a number of balls or of devices that can be taken to pieces and run down on the toboggan that is constructed 50 may be used. These latter enable the weight contained in them to be changed and their speed to be thus modified.

It is fully understood that other forms and other methods of execution may be employed and that the constructional details may also be varied. On the other hand the various constituent elements of this invention could be replaced by others acting in the same manner or giving the same result. 60

I claim,

1. A toy toboggan railway comprising flexible rails of different lengths adapted to be assembled to form straight and curved track sections, cross ties for engagement with 65 spaced holes in the rails, means for supporting the track at different heights and including upright bearers each adapted to carry a plurality of cross stays at different heights and pivoted feet on the bearers. 70

2. A toy toboggan railway comprising flexible rails of different lengths adapted to be assembled to form straight and curved track sections, means for joining the ends of adjacent rails and detachable cross ties including pins extending across the track. 75

3. A toy toboggan railway comprising rails of different lengths, adapted to be assembled to form straight and curved track sections, means for joining the ends of adjacent rails, detachable cross ties including pins extending across the track and vehicles adapted to run on the track. 80

In testimony whereof he has affixed his signature, in presence of two witnesses.

NICOLAS RÉTHORÉ.
